US0D1061182S

(12) **United States Design Patent** (10) Patent No.: **US D1,061,182 S**
(45) Date of Patent: ** Feb. 11, 2025

(54) **FISH DESCALER**

(71) Applicant: **Zhengbin Qiao**, Sichuan (CN)

(72) Inventor: **Zhengbin Qiao**, Sichuan (CN)

(**) Term: **15 Years**

(21) Appl. No.: **29/963,814**

(22) Filed: **Sep. 19, 2024**

(51) LOC (15) Cl. **07-04**

(52) U.S. Cl.

USPC **D7/696**

(58) **Field of Classification Search**

Primary Examiner — Terry A Wallace

(57) **CLAIM**

The ornamental design for a fish descaler, as shown and described.

DESCRIPTION

FIG. 1 is a front and top perspective view of a fish descaler, showing my new design.

FIG. 2 is a rear and bottom perspective view thereof.

FIG. 3 is a front view thereof.

FIG. 4 is a rear view thereof.

FIG. 5 is a left side view thereof.

FIG. 6 is a right side view thereof.

FIG. 7 is a top view thereof; and,

FIG. 8 is a bottom view thereof.

The broken lines in the figures depict portions of the fish descaler that form no part of the claimed design.

1 Claim, 8 Drawing Sheets
